UNITED STATES PATENT OFFICE.

URIAH CUMMINGS, OF BUFFALO, NEW YORK.

AIR-COMPRESSOR.

SPECIFICATION forming part of Letters Patent No. 363,509, dated May 24, 1887.

Application filed October 26, 1886. Serial No. 217,274. (No model.)

To all whom it may concern:

Be it known that I, URIAH CUMMINGS, of the city of Buffalo, in the county of Erie and State of New York, have invented a new and 5 useful Improvement in Air-Compressors, of which the following is a specification.

This invention relates to that class of air-compressors in which the air is compressed by a reciprocating piston moving in a cylinder, 10 and which are adapted to compress the air to a high pressure—for instance, as a motor in rock-drills and other machines.

The object of my invention is to produce an air-compressor of this character which can be 15 operated at a high rate of speed, and which is durable and easily kept in order.

In the air-compressors now most generally used the heat which is liberated by compressing the air is removed by injecting water into 20 the compressing-cylinder; but this is objectionable, because the water often carries solid impurities with it, which injure the contact-surfaces of the cylinder and piston to such an extent as to render the renewal of these parts 25 necessary.

My invention is designed to overcome this difficulty; and the invention consists of the improvements which will be hereinafter fully described, and pointed out in the claims.

30 In the accompanying drawings, consisting of two sheets, Figure 1 is a side elevation of my improved air-compressor. Fig. 2 is a top plan view of the same. Fig. 3 is a top plan view of the steam and air pipes. Fig. 4 is a longitudinal section of the cylinder and connecting parts on an enlarged scale. Fig. 5 is a sectional view of the air-escape valve on an enlarged scale. Fig. 6 is a similar view of the air-inlet valve on an enlarged scale.

40 Like letters of reference refer to like parts in the several figures.

A represents the horizontal bed of the air-compressor, and A' A² two horizontal cylinders secured to the same and provided, respectively, with pistons a a', which are secured to the ends of a piston-rod, a². Each cylinder is closed at its inner end by a head, b, which is provided with a stuffing-box, b', through which the piston-rod works.

50 C C' represent the steam-valves arranged, respectively, in valve-chests c c', the inner ends of which are connected with the cylinder by

ports d d', through which the steam passes to and from the inner ends of the cylinders.

E represents the steam-supply pipe provided 55 with two branch pipes, e e', which connect with the valve-chests c c' and conduct the steam to the same.

f f' represent the exhaust-ports formed, respectively, in the cylinders A' A², and connected with an exhaust-pipe, F, by branch pipes F' F'.

As shown in the drawings, the steam-valves C C' are constructed in the form of rock-valves and provided on the outer sides of the valve-chests with arms g g', which are connected by a rod, g², so that both valves move in unison. Valves of any other suitable construction may, however, be employed, if preferred.

H represents a cross-head secured to the 70 piston rod a², between the cylinders A' A², and h represents the horizontal guide-bars on which the cross-head slides, and which are supported on the bed A.

I represents a horizontal shaft provided with 75 fly-wheels I, and journaled in bearings i, formed on the bed A in rear of the cylinder A².

J represents rods which connect the cross-head H with cranks j, secured to the fly-wheel shaft I, and whereby said shaft is rotated. 80

K represents an eccentric secured to the fly-wheel shaft I, and connected with the valve arm g by a rod, k, so as to actuate the valves. The latter are so arranged with reference to their respective steam and exhaust ports that 85 one valve admits steam to its cylinder when the other exhausts.

L L' represent the air-inlet valves arranged in the outer heads, l l', of the cylinders in a well-known manner, so as to admit the external air 90 to the cylinder when the piston moves toward the opposite end of the cylinder. Each of these valves is provided with a movable disk, m, which is attached to a bolt, m', and closes against an annular seat, m². The latter is 95 formed in a casing, m³, which is provided at its outer end with openings through which the air enters, as represented in Fig. 6.

N N' represent the air-escape valves, which may be of any suitable or well-known construction. These valves are also arranged in the outer heads of the cylinders and connected by branch pipes n with an air pipe, n', by which the compressed air is conducted to a suitable 100

reservoir or to the machine or apparatus in which the air is to be used. Each of these escape-valves is provided with a movable disk, O , attached to a stem, O' , and closing against a seat, O'' , which is formed in a casing, O^3 , as represented in Fig. 5.

In the position of the parts represented in Fig. 4, the steam enters the inner end of the cylinder A' through the port d and drives the piston a toward the outer end of the cylinder, thereby compressing the air before the piston and finally forcing such air through the air-escape valve N into the compressed-air conduit. The piston a' in the cylinder A^2 is at the same time moved toward the inner end of its cylinder, and the steam escapes from before the piston a' through the exhaust-port f' , while the outer air enters the opposite end of the cylinder through the open air-inlet valve L' . During the return stroke of the pistons the steam is exhausted from the cylinder A' and air is admitted to the same, and steam is admitted to the cylinder A^2 and the compressed air is expelled from the same. In this manner each cylinder operates alternately as a steam cylinder and as an air-cylinder, and each cylinder is at every other stroke supplied with steam, whereby the inner surfaces of the cylinders and the pistons are at short intervals supplied with moisture, which insures the smooth running of the machine and prevents the parts from becoming overheated. By connecting the pistons and valves with a fly-wheel shaft, the machine can be operated at a high rate of speed. The steam-valves may be so constructed that the steam is used with a proper degree of expansion.

The heat which is generated in each cylinder by compressing the air therein is transmitted to the steam which is admitted to the cylinders and evaporates the water mixed with the steam, thereby raising the effective steam-pressure in the cylinders beyond the pressure in the steam-supply pipe and enabling the compressor to furnish compressed air for working purposes of equal or higher pressure than the steam by which the compressor is actuated. The useful effect of the steam is by this means considerably increased.

If desired, the piston-rod may be extended through the outer head of one of the cylinders, and the cross-head may be secured to the outer

end of the piston-rod, instead of being arranged between the cylinders, as shown. In this case the two cylinders can be arranged closely together, and a single steam-valve may be employed for controlling the flow of steam to and from both cylinders, instead of two separate valves, as shown.

I claim as my invention—

1. In a steam-actuated air-compressor, the combination, with two actuating-cylinders of equal diameters and two pistons working in the same and connected by a piston-rod, of a valve mechanism whereby steam is alternately admitted to one end of each cylinder and exhausted therefrom, air inlet and escape valves, through which the air is alternately admitted to and emitted from the opposite end of each cylinder, and a fly-wheel and shaft rotated from said piston-rod and operating said valve mechanism, substantially as set forth. 55

2. In a steam-actuated air-compressor, the combination, with two actuating-cylinders of equal diameters and two pistons working in the same and connected by a piston-rod, of separate steam-valves, one applied to each cylinder, whereby steam is alternately admitted to each cylinder and exhausted therefrom, air inlet and escape valves, through which air is alternately admitted to and emitted from the opposite end of each cylinder, and a fly-wheel and shaft connected with the piston-rod between the cylinders, substantially as set forth. 70

3. In a steam-actuated air-compressor, the combination, with two actuating and compressing cylinders and two connected pistons working in the same, of a valve mechanism whereby steam is alternately admitted to one end of each cylinder and exhausted therefrom, air-inlet valves through which external air is alternately admitted to each cylinder, air-escape valves through which the compressed air is alternately emitted from each cylinder at the same pressure, and a fly-wheel and shaft rotated from said pistons, substantially as set forth. 85 90 95

Witness my hand this 23d day of October, 1886.

U. CUMMINGS.
